UNITED STATES PATENT OFFICE.

DAVID M. THOMPSON, OF PROVIDENCE, RHODE ISLAND.

STEAM-GENERATOR.

SPECIFICATION forming part of Letters Patent No. 601,486, dated March 29, 1898.

Application filed June 2, 1897. Serial No. 639,095. (No model.)

To all whom it may concern:

Be it known that I, DAVID M. THOMPSON, of Providence, in the county of Providence and State of Rhode Island, have invented a new and useful Improvement in Steam-Generators; and I hereby declare that the following is a full, clear, and exact description of the same, reference being had to the accompanying drawings, forming part of this specification.

This invention has reference to an improvement in steam-boilers and furnaces connected therewith.

In the economic generation of power the steam-generator performs the most important function, because the most perfect steam-engine can utilize only a portion of the heat stored up in the steam-generator. To secure the best and most economic results, the fuel must be burned under the most favorable conditions possible for the perfect combustion of the carbon in the fuel and of the volatile gaseous products disengaged by the heat and the disintegration of the fuel on the grate. Not only must the proper quantity of air be supplied to the fuel and the gases, but the gases must have ample room to expand, time for each atom to combine with the oxygen of the air, and, above all, the gaseous products must be maintained at a high temperature until every atom of carbon is consumed and converted into heat.

The heat produced by the combustion of fuel may be divided into the heat of the products of combustion, which in passing through the flues or tubes of the steam-generator is absorbed by the water and stored up for useful work, and radiated heat, which can be reflected and deflected, but always acts locally on the surfaces surrounding the incandescent fuel or flame.

One object of this invention is to construct the furnace of a steam-generator so that the gaseous products of combustion may expand and, while the atomic mixture is facilitated, be maintained at a high temperature to facilitate the perfect combustion of the same.

Another object of the invention is to so arrange the furnace that the expanded mixed and highly-heated products of combustion from one grate will pass over the incandescent fuel of another grate and then enter a com-

bustion-chamber before they enter the tubes of the steam-generator.

Another object of the invention is to utilize 55 the radiated heat of a furnace of the above-mentioned construction by conducting the same into the feed-water supplied to the generator.

Another object of the invention is to prevent 60 the deposit of soot in the tubes of a steam-generator and the discharge of black smoke; and another object of the invention is to more completely separate the impurities held in suspension in the feed-water before 65 the water enters the main body of the steam-generator.

To these ends the invention consists in the peculiar and novel construction of the furnaces and the combination of the parts, as 70 will be more fully described hereinafter and more particularly pointed out in the claims.

I have elected to illustrate in the drawings the furnaces as applied to a vertical tubular boiler, showing the preferred form of construction, but do not wish to confine myself 75 to the use of the furnaces in connection with this particular form or construction of the boiler.

Figure 1 is a vertical sectional view showing 80 the furnaces in connection with a vertical tubular steam-boiler and auxiliary water-tube steam-generators. Fig. 2 is a transverse sectional view of the furnaces, showing the water-jacket inclosing the furnaces and the 85 generating-tubes extending through the furnaces. Fig. 3 is a horizontal section on the line X X of Fig. 1, showing the flame-chamber connecting the two furnaces.

Similar letters of reference indicate corresponding parts in all the figures.

In the drawings, A indicates the furnace to which fuel is being supplied or has last been supplied, and A' the furnace in which the fuel is in the incandescent state after the more 95 volatile carbon has passed off. The two furnaces are separated by the partition-wall A², which extends from the front to or nearly to the end of the grates A³ A³. They are inclosed by the side walls A⁴ A⁴ and covered by 100 the arches A⁵ A⁵, preferably of fire-brick, resting on the side walls and the partition-wall A².

The two furnaces A and A' are connected at the rear by the large preferably semicircu-

lar flame-chamber A⁶ and at the front by the opening A⁷, in which the swinging gate A⁸ is placed. This gate A⁸ controls the exit from the furnaces to the combustion-chamber A⁹, and by swinging the gate from one side to the other either one of the furnaces may be connected with the combustion-chamber A⁹. Under the grates are the ash-pits A¹⁰ A¹⁰ and on the rear ends of the grates are the bridge-walls 10 A¹¹ A¹¹. An opening connects the rear of the ash-pits with the vault A¹², in which the car A¹³ forms a convenient receptacle for the removal of the ashes.

The jacket A¹⁴ extends over the side walls 15 of the furnaces around, the wall of the flame-chamber, and over the arch of the combustion-chamber. The jacket is made up of sections containing each two or more compartments A¹⁵, separated by partitions having the 20 openings A¹⁶ to form connections between all the chambers or cells in each section. The sections are connected by the pipes A¹⁷ with the water-supply and with the pipes A¹⁸, by which the heated water is delivered directly 25 to the boiler or to a settling-chamber connected with the boiler, as is shown in Fig. 1, or to a pump, by which it is delivered to the boiler.

The furnaces are provided with any suitable fire and ash-pit doors and devices for controlling the draft and air-supply.

I will now describe the operations of the furnaces in their normal condition when the fires have been burning for a sufficient time 35 to heat the fire-brick sides and arches and with the gate A⁸ in the position shown in Fig. 2, using bituminous or other coal liable to produce the objectionable black smoke.

The coal supplied in the usual manner to 40 the fire in the furnace A is, owing to the fire and the great heat of the fire-brick or other refractory material of the sides and arch of the furnace, quickly heated, so as to rapidly disengage the volatile gases rich in carbon. 45 These gases and the air drawn into the furnace expand and pass in nearly straight currents over the bridge-wall and enter the semi-circular arched space of the flame-chamber, where by the change in the direction of the 50 currents, the shape of the arched roof, the increased area of the chamber, and the heat of the walls the gases and air mix and burst into flame. The complete combustion of all the carbon in the gases and the prevention of 55 smoke is so much a matter of atomic mixture, time, and heat that to secure the desired result I pass the gases from the flame-chamber through the furnace A', over the incandescent fuel on the grate of this furnace, and 60 through the draft-opening A⁷ into the arched combustion-chamber A⁹, where the now thoroughly mixed and heated gases can again expand and, under the influence of the heat of this chamber, form a final and complete union 65 of the oxygen of the air with any atoms of carbon still remaining in the products of combustion.

Two arched openings A²⁰ A²⁰, lower than the arch of the combustion-chamber A⁹, connect the combustion-chamber with the chamber A²¹ under the vertical tubular boiler B and permit the heated products of combustion to pass through the tubes of the boiler to the chimney. The heated products of combustion may be conveyed from the combustion-chamber A⁹ to any other form or construction of boiler.

The combustion of the fuel in this furnace is so complete that, as no carbon can pass through the boiler, the smoke is of a light 80 color, nearly invisible, because it contains no coloring-matter. No soot collects in the tubes or on any other part of the boiler, and fine ashes are collected in the flame-chamber, the combustion-chamber, and the chamber A²¹, 85 because by the increased area of these chambers the velocity of the flow of the gases is reduced and ashes or incombustible matter is precipitated in these chambers.

The boiler B, preferably used in connection 90 with the furnaces, as shown in Fig. 1, is a vertical tubular boiler having the central open space B', surrounded by the tubes B². The central space B' connects with the central water-column B³, extending from the lower 95 tube-sheet of the boiler downward to the mud-drum B⁴. The circulating-tube B⁵, preferably provided with a funnel-shaped upper end, is placed into the water-column B³ and divides the same into a central descending and an annular ascending space.

The mud-drum B⁴ connects with the transverse chamber B⁶, provided on the two opposite sides with the mud-drums B⁷ B⁷. The blow-off pipes B⁸ B⁸ connect with the mud-drums B⁷ B⁷ and the blow-off pipe B⁹ connects with the mud-drum B⁴. These blow-off pipes are provided with proper gate-valves, as shown in Fig. 1, and the impurities collected in these mud-drums may be discharged 100 through these blow-pipes from the bottom of the mud-drums as often as the nature of the water used requires.

The series of water-tubes B¹⁰ are connected with the transverse chamber B⁶ above the two 115 mud-drums B⁷ B⁷ and extend upward through the flame-chamber on an easy curve and extend in an upward-inclined direction through the furnaces A and A' and have their other ends secured in one of the chambers B¹¹ B¹¹, 120 located at the front of the boiler, which front is provided with suitable doors by which access is had to the chambers B¹¹. Another series of water-tubes B¹² extend in an inclined direction from each of the chambers B¹¹, 125 through the combustion-chamber A⁹ and the chamber A²¹, to the fitting B¹³, which is connected with the steam-generator by the pipe B¹⁴. A pipe B¹⁵ extends from each of the fittings B¹³ downward and connects the same 130 with one of the mud-drums B⁷. By this construction the two water-tube sections, one from each furnace, are in all respects independent of each other and free to expand and

contract. The steam generated in each is delivered by the pipe B¹⁴ to the boiler, and perfect circulation of the water in each section is secured by the pipe B¹⁵, which forms a direct connection between the upper ends of the water-tubes of each section with the lower water connection of the tubes. The rapid circulation of the water in these tubes B¹⁰ and B¹² and their exposure to the direct action of the rays of heat from the fire and the flame in the furnaces inclosed by the refractory material secures an evaporative efficiency of the highest value.

The feed-water, as has been hereinbefore described, is heated in the cellular jacket A¹⁴, the several sections of which are connected with the pipe A¹⁸. The pipe B¹⁶ may connect the pipe A¹⁸ with the feed-pipe B¹⁷, as is shown in Fig. 1; but I prefer to connect the pipe A¹⁸ with a steam or feed pump and connect the pump with the feed-pipe B¹⁷, so as to relieve the cellular jacket from the pressure of the steam and the static pressure of the water in the boiler and subject the jacket only to the pressure incident to the weight of the water in the jacket. The feed-pipe terminates, preferably, in a rose B¹⁸, and the feed-water is delivered into the mud-drum B⁴ preferably at a point below the ash-pit.

I will now more fully describe the effect of the arrangement described on the water used in the generation of steam. As before described, the feed-water is supplied first to the cellular jacket A¹⁴, and its temperature is raised by the absorption of the heat conducted through the fire-brick or similar lining of the furnaces. The feed-water is preferably supplied to the lowest part of the jacket from a tank, the water-level in which is maintained but little above the highest part of the jacket.

The water heated in the cellular jacket is preferably delivered by the pipe or pipes A¹⁸, connected with the upper part of each section of the jacket, to a tank, from which it is forced into the boiler by means of a feed-pump connected with the feed-pipe B¹⁷. The pipe A¹⁸ may be connected directly to the feed-pump, or, if the cellular jacket A¹⁴ were strong enough to withstand the pressure, the feed-water might be forced by the feed-water pump into the lower part of the jacket and the upper part of the jacket might be connected directly by the pipe B¹⁶ with the feed-pipe B¹⁷. In either arrangement the feed-water is heated to or nearly to the boiling-point in the cellular jacket, and its temperature is materially increased in its passage through the feed-pipe from the upper end of the boiler to the mud-drum, where it is preferably delivered in a divided state or spray.

When water is heated, the capacity to hold matter in suspension is diminished. The feed-water discharged from the feed-pipe into the mud-drum precipitates the impurities contained in it. A large part of the feed-water enters into the transverse chamber B⁶

and passes through the water-tubes B¹⁰ and B¹² into the fitting B¹³. The steam generated in this passage and some of the water enter the boiler through the pipe B¹⁴, and the greater portion of the water descends through the pipe B¹⁵ to the mud-drum B⁷, where the now more concentrated water deposits the impurities held in suspension, and the purified water reenters the water-tubes B¹⁰ and some of it the mud-drum B⁴, while a portion of the water required mixes with the water descending through the circulating-tube B⁵ and ascending through the annular space between the circulating-tube B and the column B³. This continuous circulation of the water in the boiler, by which the water, made denser by the partial conversion into steam, descends to the mud-drums and reascends in contact with the heating-surface, so facilitates the separation of the impurities and their precipitation in the mud-drums, where they are not affected by heat and may be readily blown off, that in practice after an extended use with inferior water not the slightest precipitation of impurities or scale is found on the tube-surfaces or tube-sheet of the boiler. Efficiency and durability are secured by this arrangement.

In practice the furnaces are alternately fired. The firing and ash-pit doors of the furnace that is being fired are open and the draft-opening A⁷, controlled by the gate A⁸, is closed, while the firing and ash-pit doors of the other furnace are closed and the draft-opening A⁷ of this other furnace is open. When the other furnace is fired, the gate A⁸ is reversed. The gate A⁸ may be connected by suitable mechanism with the furnace-doors, so that by opening the firing-door of a furnace the gate is swung over to close the outlet of this furnace and compel the gases to pass through the flame-chamber and, the furnace not being fired, through the draft-opening A⁷ to the combustion-chamber.

Having thus described my invention, I claim as new and desire to secure by Letters Patent—

1. In combination with a steam-boiler, a furnace divided by a partition into two separate firing-chambers, a flame-chamber in the rear of and connecting the two firing-chambers, and a draft-opening in the front end of the firing-chamber controlled by a gate, whereby the products of combustion from one firing-chamber are made to pass through the flame-chamber and over the fire in the other firing-chamber, as described.

2. In combination with a steam-boiler, a furnace inclosed by walls of some refractory material, a partition dividing the furnace into two separate firing-chambers, a flame-chamber in the rear of and connecting the two firing-chambers, and a draft-opening in the front end of the firing-chambers controlled by a gate, whereby the products of combustion from one firing-chamber are made to pass

through the flame-chamber and through the other firing-chamber before entering the tubes of the boiler, as described.

3. In a steam-generator, the combination with the steam-boiler, of a furnace having two separate firing-chambers, a flame-chamber in the rear of and connecting the two firing-chambers, a draft-opening controlled by a gate, and a combustion-chamber; the whole inclosed by fire-brick, whereby the products of combustion from one firing-chamber are made to pass through the flame-chamber, through and over the fire in the other firing-chamber and through the combustion-chamber before they enter the tubes of the steam-boiler, as described.

4. In combination, a steam-boiler, a furnace divided by a partition into two separate firing-chambers, a flame-chamber connecting the rear of the two firing-chambers, a draft-opening at the front end of the firing-chambers, a combustion-chamber, and a cellular water-jacket inclosing the furnace, whereby the more perfect combustion of the fuel is secured before the products of combustion enter the tubes of the boiler and radiated heat is transmitted by the brick lining to the water in the jacket, as described.

5. In combination, a steam-boiler, a brick-inclosed furnace divided by a partition into two firing-chambers connected at the rear by a flame-chamber and at the front by a draft-opening with a combustion-chamber, of a series of water-tubes, extending through the furnace, connected with the mud-drum of the boiler and with the boiler, whereby the more perfect combustion of the fuel is secured before the products of combustion enter the flues of the boiler and the radiated heat is locally utilized by the water-tubes, as described.

6. In combination with a steam-boiler and a furnace divided by a partition into two separate firing-chambers adapted to be alternately fired, of two separate sections of water-tubes, one section for each firing-chamber, each section connected with the mud-drum below the furnace and with the boiler above the furnace, whereby the sections may adjust themselves to variations in temperature, as described.

7. In a steam-generator, the combination with a vertical tubular boiler having a central water-column connected with a mud-drum at its lower end, of the transverse chamber B^6 provided with the mud-drums B^7 B^7 , a

series of water-tubes B^{10} and B^{12} , connections between the water-tubes, the chamber B^6 and the boiler, and a furnace located on one side of the central water-column of the boiler, whereby the heat of the fire is exerted on the water-tubes before the products of combustion enter the flues of the boiler and the efficiency of the boiler increased, as described.

8. In a steam-generator, the combination with the vertical tubular boiler B , the water-column B^3 , the circulating-tube B^5 and the mud-drum B^4 , of the feed-water pipe B^{17} and the rose B^{18} connected with the feed-water pipe below the ash-pit, whereby the feed-water is sprayed into the mud-drum and the precipitation of impurities facilitated, as described.

9. In combination, a vertical tubular steam-generator, a central water-column extending from the lower tube-sheet downward, a circulating-tube within the central water-column, a mud-drum at the bottom of the central water-column, a feed-water pipe extending from the top of the boiler downward and terminating in the mud-drum, a transverse chamber connected with the mud-drum and provided with auxiliary mud-drums, a series of water-tubes connected with the transverse chamber, with the boiler and with the mud-drums of the transverse chamber, and a furnace divided by a partition into two firing-chambers and adapted to be alternately fired, as described.

10. In a steam-generator, the combination of the following instrumentalities, a furnace divided by a partition into two arched firing-chambers, a semicircular arched flame-chamber connecting the rear of the two firing-chambers, an arched combustion-chamber above and extending across the width of the firing-chambers, a draft-opening, controlled by a gate, connecting the firing-chambers with the combustion-chamber, a cellular water-jacket inclosing the furnace structure, and a steam-boiler connected with the combustion-chamber, whereby the fuel is consumed within spaces surrounded by fire-brick and the products of combustion passed through the tubes of the steam-boiler, as described.

In witness whereof I have hereunto set my hand.
